[57] CLAIM

The ornamental design for a dispenser spout for a squeeze-type container, as shown and described.

DESCRIPTION

FIG. 1 is a front perspective view of a dispenser spout for a squeeze-type container showing our new design, portions of a container shown in broken lines for convenience of illustration;

FIG. 2 is a side elevational view thereof, portions of a container shown in broken lines for convenience of illustration, the opposite side not shown being substantially a mirror image thereof.

The rear of the spout is unornamented and smoothly curved.
